SCORING DEVICE FOR EXAMINATION PAPERS

William J. Kennerly, Montevallo, Ala.

Application November 25, 1943, Serial No. 511,701

6 Claims.

(Cl. 35—48)

This invention relates to a device for grading examination papers of the selective answer type and has for an object the provision of a device of the character designated which shall be simple of design and operation and by means of which such examination papers may be speedily and accurately graded with a minimum of error.

A more specific object of my invention is to provide a grading device for examination papers of the selective answer type which shall include a frame for holding the paper, and means associated with the frame for covering selected portions of the paper.

Briefly, my invention comprises a device of the character designated which includes a frame adapted to receive an examination paper to be graded, which examination paper is preferably of the standard letter size to facilitate handling and filing. A cover for the frame fits over the sheet and is provided with a plurality of columns of slots which register with the printed enclosures provided on the sheet for the selective answers. Movable slides cooperate with the slots to cover selected portions of the printed enclosures, preferably those which indicate the correct answers, whereby the person using the device may see at a glance the number of correct and incorrect answers on the paper and grade accordingly.

In the accompanying drawing forming a part of this application:

Fig. 1 is a plan view of my improved device;

Fig. 2 is an edge view of the same;

Fig. 3 is a fragmentary view of a typical selective answer form of examination paper;

Fig. 4 is a detail sectional view showing the construction of the cover and movable slides;

Fig. 5 is a fragmentary detail view of the rear of the cover.

Referring to the drawing, I show in Fig. 3 an example of the type of examination paper which my device is adapted to use. The paper, shown at 10, is preferably a standard, letter size sheet and has printed thereon a plurality of columns of rows of printed enclosures 11, which are numbered or otherwise identified according to the choice of answer in the selective type examination. In the example shown, there are four such enclosures in each row, numbered 1 to 4 inclusive at the top, indicating four selective answers which may be made to each question, although any desired number of such enclosures may be provided. Also, the letters "T" and "F" may be employed over two of the enclosures to provide for the "true or false" type of examination question. The rows of printed

enclosures forming the columns are numbered consecutively to correspond to the numbered questions to be answered.

At 12, I show a frame which forms an enclosure in which the examination paper 10 is adapted to fit snugly. The frame 12 is provided with a backing 13 for holding the examination paper, and a cover 14 which fits snugly within the frame over the backing 13 and examination paper 10. The cover 14 is hinged to the frame 12 by means of hinges 16 and a suitable tab 17 is provided on the side for opening and closing it.

The cover 14, as shown in Fig. 1, is formed with a plurality of columns of slots 18 corresponding to the columns of printed enclosures on the examination paper 10 and bearing numerals and other identifying marks corresponding to the identifying marks on the examination paper. When the paper is placed in the frame and the cover closed down over it the slots register directly with the several rows of printed enclosures and the rows are numbered consecutively corresponding to the numbers of the questions to be answered. An additional slot 19 is provided at the bottom of each of the columns and may be employed to indicate on the examination paper the number of questions answered correctly under the letter "R," or incorrectly under the letter "W" and the per cent or grade made by the person taking the examination.

Each of the slots 18 has fitted therein one or more movable slides 21 each of which is adapted to cover one of the printed enclosures and, when so used is set to cover the printed enclosure indicating the correct answer to a question. Thus when the paper is being graded, only the incorrect answers on the examination paper will show through the slots 18 and the paper may be graded instantly. Also, the person grading the paper may, if desired, mark through the slots all the incorrect answers so that when the paper is returned to the person taking the examination, he may see exactly the mistakes made. If desired, a plurality of slides 21 may be employed in each slot and set to cover all the printed enclosures in each line except the one, which indicates the correct answer to a question. When so used, the device shows instantly the number of correct answers made by the person taking the examination and the paper be graded accordingly.

Referring to Figs. 4 and 5, I show in detail the manner of mounting the slides 21. At 22 are shown the partitions between the slots 18, each of which is rabbeted as shown at 23 on both sides and the slides 21 are provided with overhanging

flanges 24 fitting into the rabbets along the partitions so that they lie flush with the front surface of the cover and are less liable to be accidentally misplaced. The slides 21 may be held in place by means of spring clips such as shown at 26 pivotally mounted at 27 to the backs of the slides whereby they may be turned as indicated in Fig. 5 in dotted lines to remove or replace them in the slots. There may thus be employed a single slide, or a plurality of slides in each slot as heretofore mentioned in this description. Along the inner surface of the division 22, in the rabbet 23, I provide a series of indentations 28 and provide slight projections 29 on the spring clips 26 to engage in the projections 29 on the spring clips 26 to engage in the projections 28 and hold the slides in place against accidental displacement. The spring clips lie flush or below the inner surface of the cover 22 so that the slides are not engaged by papers being placed or removed from the frame.

From the foregoing the use of my improved device will be readily understood. The examination questions, not shown, are well understood to consist of a plurality of numbered questions, each indicating a choice, or selection of answer, and may comprise a multiplicity of choices, or be in the alternative form, as with "true" and "false" type of questions. The slots on the cover 14 register with the numbered enclosures provided on the examination paper, and being numbered to correspond to said printed enclosures, provide the means for quicker grading of each paper. The plurality of columns are intended to afford a succession of examinations on the same subject whereby a student may have a visual indication of the progress being made in such subject. Further, by using a single slide in each slot, the correct as well as the incorrect answers may be indicated quickly and accurately on each examination, which is a further aid to the person taking the examination. Any suitable materials may be employed in the construction of my improved device, but I prefer such materials as will provide lightness and strength.

While I have shown my invention in but one form, it will be obvious to those skilled in the art that it is not so limited, but is susceptible of various changes and modifications, without departing from the spirit thereof, and I desire, therefore, that only such limitations shall be placed thereupon as are specifically set forth in the appended claims.

What I claim is:

1. In a scoring device for examination papers of the selective answer type having a plurality of regularly spaced identified enclosures printed thereon corresponding to similarly identified selective answers to an examination question, a frame in which the examination paper is adapted to fit, a cover for the frame adapted to hold the examination paper in place and having an open-

ing therein registering with the printed enclosures, and a movable slide fitting in the opening and adapted to cover a selected portion of the printed enclosures.

2. In a scoring device for an examination paper of the selective answer type having a column of regularly spaced lines of identified enclosures printed thereon corresponding to similarly identified selective answers to a plurality of examination questions, a frame in which the examination paper is adapted to fit, a cover fitting snugly into the frame and adapted to lie over the examination paper and hold it in the frame and having a column of slots therein registering with the column of lines of identified enclosures on the examination paper, and a movable slide mounted in each of the slots and adapted to cover a selected portion of the identified enclosures printed on the examination paper.

3. A device as defined in claim 2 in which a plurality of slides are mounted in each of the slots, and spring clips rotatably mounted on the backs of the slides in position when turned to engage the sides of the slots for detachably holding the slides in place.

4. A device as defined in claim 2 in which the partitions between the slots in the frame cover are rabbeted above and below each of the openings at front and rear and the slides are formed to fit into the said rabbets flush with the upper surface of the cover, spring clips rotatably mounted on the backs of the slides for removably holding the slides in place and fitting into the rabbets in the lower surface of the cover when turned to holding position, and depressions in the lower surface for engaging the spring clips and preventing accidental displacement of the slides.

5. A grading device for examination papers of the selective answer type having regularly spaced enclosures printed thereon for indicating choice of answer, comprising a frame adapted to receive a paper to be graded, a hinged cover for fitting said frame and holding the paper in place, said frame having slots therein adapted to register over the printed enclosures on the said examination paper, and slides in the slots for covering selected portions of the printed enclosures.

6. A grading device for examination papers of the selective answer type having a plurality of columns of regularly spaced enclosures printed thereon for indicating choice of answer, comprising a frame in which a paper to be graded is adapted to fit, a hinged cover for the frame having a plurality of columns of slots formed therein corresponding to the columns of printed enclosures on the paper and adapted to hold the paper in place, and means cooperating with the slots for covering selected portions of the printed enclosures.

WILLIAM J. KENNERLY.
